CHARLES LE G. FORTESCUE, OF PITTSBURGH, PENNSYLVANIA, ASSIGNOR TO WESTINGHOUSE ELECTRIC AND MANUFACTURING COMPANY, A CORPORATION OF PENNSYLVANIA.

SHIELDING SYSTEM FOR VAPOR-CONVERTERS.

1,231,587.

Specification of Letters Patent.

Patented July 3, 1917.

Application filed August 9, 1915. Serial No. 44,428.

To all whom it may concern:

Be it known that I, CHARLES LE G. FORTESCUE, a subject of the King of Great Britain, and a resident of Pittsburgh, in 5 the county of Allegheny and State of Pennsylvania, have invented a new and useful Improvement in Shielding Systems for Vapor-Converters, of which the following is a specification.

10 My invention relates to shielding systems for vapor converters, and it has for its object to provide systems of the character indicated that shall minimize short circuiting and reverse arcing, and otherwise improve 15 the operation in an apparatus of the character above specified.

The single figure of the accompanying drawing is a side view, partially in elevation and partially in section, of a vapor converter embodying a preferred form of my 20 invention.

In the operation of vapor converters and similar evacuated electric apparatus, current is conveyed between the electrodes by a 25 stream of negative electrons, emitted by the cathode and proceeding to the anode. The stream of electrons at the cathode may be excited by any of several well known methods, chief among which are the maintenance of a keep-alive arc to the cathode, the 30 maintenance of the cathode at incandescence, the impacts of a stream of positive ions thereagainst, and the impact of a beam of ultra-violet light.

35 If, in its passage from the cathode to an anode, a negative electron collides with a particle of residual gas, the particle is broken up into positive ions and negative electrons, both of which receive an initial 40 impulse toward the anode by the impact. The newly freed negative electron moves on very rapidly because the propelling force of the electrostatic field is substantially coincident in direction with the initial impulse. 45 thus given, but the newly freed positive ion moves but slowly and may soon come to rest and even reverse its direction of movement because of the neutralizing influence of the electrostatic field upon the initial impulse.

50 Furthermore, the acceleration tending to be imparted to the positive ion by the electrostatic field is much less than that of the negative electrons because of the vastly larger mass of the former, although carrying an equal charge. The delivery of a

glancing blow to a gas particle by a negative electron may disrupt the particle and force the resultant bodies more or less transversely to the arc path into comparatively weak fields of electrostatic force.

50 The passage of an anode to a condition of negative polarity with respect to the cathode, such as happens periodically in a vapor converter, finds a large number of free positive ions afloat in and near the arc 65 path without any well defined motion in any direction. These "tramp" ions are now attracted to the temporarily negative anode and, if in sufficient number and sufficiently accelerated, they may bombard the electrode 70 so energetically as to break down the negative-electrode reluctance thereof, causing short circuiting or reverse arcing within the apparatus. This harmful action is especially liable to take place if the positive ions 75 impinge upon a globule of mercury or other foreign matter upon the electrode surface. By my invention, I provide means and apparatus whereby these tramp ions are neutralized and their harmful action prevented. 80

85 Referring to the accompanying drawing for a more detailed understanding of my invention, I show a vapor converter of the metal-case type at 1, said converter embodying a solid anode 2 and a cathode 3, preferably formed of vaporizable reconstructing material, such, for example, as mercury or suitable amalgams. The anode 2 and the cathode 3 are connected, respectively, to the terminals of a source of alternating 90 current 4 through a load 5, and the cathode 3 is maintained in an active position by any suitable means, such, for example, as a keep-alive circuit 6. The anode 2 is surrounded and protected by a shielding system similar 95 to that shown and claimed in a copending application of S. W. Farnsworth, Serial No. 44,429, filed Aug. 9, 1915, and assigned to the Westinghouse Electric & Manufacturing Company. Briefly, said shielding system 100 embodies a conducting cylindrical casing 7 supporting a pair of transverse perforated plates 8 and 9. Conducting tubular members 10—10 are mounted in the perforations of the plates 8 and 9, and the two groups 105 of conducting tubular members are connected, respectively, to adjustable points in a resistance member 11 connected between the anode 2 and the cathode 3. By suitably adjusting the points of connection to 110

the resistance member 11, the tubular members 10—10 may be charged to any desired intermediate potential between those of the electrodes.

5 In the operation of my device, when the anode 2 is positive with respect to the cathode 3, a stream of negative electrons proceed from the latter through the tubular members 10—10 to the anode 2—2. As 10 above pointed out, at the instant of reversal of polarity to the anode 2, there will remain a large number of free positive ions in the arc path, forming a positive space charge. By the suitable adjustment of the potential 15 of the tubular members 10—10, this harmful positive space charge may be neutralized to any desired extent, the tendency of the positive ions to form cathode spots on the tubular members 10—10 not producing arcing 20 because of the choking effect of the resistance member 11.

My device is distinguished in its operation from that disclosed in the Farnsworth application above referred to in that the potential 25 of the suppressor shields may be adjusted within wide limits and, thus, the positive space charge may be neutralized to any desired degree, as is found essential in operation.

30 Throughout this description, I have explained the action of my device in accordance with the theory which seems most plausible in view of the present knowledge of the underlying phenomena. I desire it to be 35 distinctly understood, however, that I do not confine myself to said theory of operation but merely present the same to aid in an understanding of the invention.

While I have shown my invention in its 40 preferred form, it will be obvious to those skilled in the art that it is susceptible of various minor changes and modifications without departing from the spirit thereof, and I desire, therefore, that only such limitations shall be placed thereupon as are imposed by the prior art or are specifically set forth in the appended claims.

I claim as my invention:

1. In a vapor converter, the combination 45 with a pair of electrodes, of means for initiating and maintaining an arc therebetween, a conducting member mounted to embrace said arc, and means for adjusting the potential of said member to that of either electrode or to any intermediate value.

2. In a vapor converter, the combination 50 with a pair of electrodes, of means for initiating and maintaining an arc therebetween, a plurality of conducting members arranged

to embrace said arc in succession, and means 60 for independently adjusting the potential of either conducting member to that of either electrode or at any intermediate value.

3. In a vapor converter, the combination 65 with a pair of electrodes, of means for initiating and maintaining an arc therebetween, a conducting member mounted to embrace said arc, and means for adjusting the potential of said member to that of either electrode or at any intermediate value, independently 70 of the flow of electronic current therefrom.

4. In a vapor converter, the combination 75 with a pair of electrodes, of means for initiating and maintaining an arc therebetween, a connection including a current-limiting device joining said electrodes, a conducting member embracing a portion of the arc path, and means for connecting said conducting member to any desired point in 80 said current-limiting device.

5. In a vapor converter, the combination 85 with a pair of electrodes, of means for initiating and maintaining an arc therebetween, a connection including a current-limiting device joining said electrodes, a plurality of conducting members embracing different portions of the arc path, and means for independently connecting each of said 90 conducting members to any desired point in said current-limiting device.

6. In a vapor converter, the combination 95 with a pair of electrodes, of means for initiating and maintaining an arc therebetween, a connection including a current-limiting device joining said electrodes, a group of tubular conducting members disposed in the arc path, means for forcing the arc to traverse said members, and means for connecting any of said conducting members to 100 any desired point in said current-limiting device.

7. In a vapor converter, the combination 105 with a pair of electrodes, of means for initiating and maintaining an arc therebetween, a connection including a current-limiting device joining said electrodes, a plurality of groups of tubular conducting members, means for forcing said arc to traverse 110 the members of each of said groups in succession, and means for independently connecting each of said groups to any desired point in said current-limiting device.

In testimony whereof, I have hereunto 115 subscribed my name this 28th day of July, 1915.

CHARLES LE G. FORTESCUE.
